GEORGE RALPH PAYNE AND STEWART MOORE, OF TEXARKANA, TEXAS, ASSIGNEES
TO TEXARKANA PIPE COMPANY, OF TEXARKANA, TEXAS.

SEPTIC TANK.

1,058,458.

Specification of Letters Patent.

Patented Apr. 8, 1913.

Application filed October 11, 1912. Serial No. 725,244.

To all whom it may concern:

Be it known that we, GEORGE R. PAYNE and STEWART MOORE, citizens of the United States, and residents of Texarkana, in the 5 county of Bowie and State of Texas, have invented certain new and useful Improvements in Septic Tanks, of which the following is a specification.

Our invention relates to septic systems of 10 sewage disposal, our object being to provide certain improvements in the construction of the septic tank itself, whereby the system as a whole may be readily and quickly installed, and its capacity, either before or 15 after installation, readily adjusted to suit existing conditions.

Other objects, and the resulting advantages, of our present improvements, would appear in the course of the following description, in which reference is made to the accompanying drawing, forming a part of 20 this specification, and in which—

Figure 1 is a central longitudinal section through a septic system; and Fig. 2 is a 25 transverse section taken therethrough substantially on the line 2—2 of Fig. 1.

Referring to these figures, the septic system, to which our invention is directed, comprises, as usual, a filter tank A and a septic 30 tank B, the filter tank comprising a vertically disposed section of pipe having diametrically opposed inlet and outlet branches a and a' respectively, arranged adjacent its upper end. The tank A is filled with filtering material A' up to a point flush with 35 the inlet and outlet branches, from the latter of which leads a discharge pipe A² through which substantially clear water is discharged as a result of the passage of the 40 sewage through the system and the manner in which it is acted upon therein.

The septic tank B is formed of a plurality of cylindrical pipe sections b, b' and b², the contiguous ends of which sections are 45 coupled in any suitable manner whereby to form a substantially cylindrical casing which is arranged horizontally in the ground and connected by a pipe C with the inlet branch a of the filter tank A, said pipe C leading 50 through an end cap b³ closing the outer end of the end section b of the casing B.

The opposite end of the casing of the septic tank is closed by an end plate b⁴, and each of the sections thereof is provided 55 with an upper clean out hole b⁵ which

is normally closed and which is designed to receive the end of the inlet pipe D should such be necessary, this inlet pipe being let into the end section of the septic tank opposite to that end from which the discharge 60 pipe C extends. In the present instance, as shown, the inlet pipe D is let into the end section b² through its upper clean out hole b⁵. Upon the interior of the casing, the several sections b, b' and b² are partially separated by baffle plates E which are of a height less than the diameter of the casing, and thus provide for an overflow from one compartment of the casing to another while providing against the communication of the 70 liquid disturbances. This is an important feature of our invention, inasmuch as in the normal operation of the system the sewage coming in through the inlet pipe D would otherwise disturb the anaerobic germs 75 throughout the entire casing. In view of our arrangement, however, this disturbance is limited to the space within the section b², the end plate b⁴ and baffle plate E upon opposite sides of this section being provided 80 with inwardly extending lips e and b⁶ respectively in order to further the effect above mentioned.

It is to be understood that while the septic tank B may be formed of any suitable material which is impervious to moisture and not subject to disintegration through the action of sewage gases, we prefer that it be made of vitrified clay throughout, inasmuch as this material, we have found, fulfills all 85 requirements and provides a perfectly sanitary system which may be placed with safety beneath a residence, or even adjacent to a well from which drinking water is secured. 90

It is to be understood further that in providing a septic tank which is disposed horizontally, we have rendered the installation of a septic system much more ready and convenient, and that in forming the casing 100 in separable sections, we effectively provide for its adjustment in capacity to suit existing conditions before installation, or varying or changed conditions thereafter.

We claim:

1. A septic tank comprising a horizontal substantially cylindrical casing embodying a plurality of separable sections, separable end plates closing the ends of the casing and one of which is provided with an outlet, each 110

- of said sections of the casing having means whereby to receive an inlet; and baffle plates spaced from one another within the casing and of a height less than that of the casing.
5. 2. A septic tank comprising a horizontal substantially cylindrical casing having an inlet and an outlet and comprising a plurality of separable sections, end plates closing the ends thereof, and baffle plates of a height less than that of the casing and disposed therein, said baffle plates being held between the contiguous ends of the said sections.
3. A septic tank comprising a horizontal substantially cylindrical casing embodying a plurality of separable sections, separable end plates closing the ends of the casing, one of the end sections of said casing having an inlet, the other end section having 15 an outlet; and baffle plates spaced from one another within the casing and secured between the adjacent ends of the several sec-
- tions of the casing, said baffle plate and said end plate upon opposite sides of the inlet section having inwardly projecting 25 horizontal lips for the purpose described.
4. A septic tank comprising a plurality of cylindrical pipe sections, the contiguous ends of which are separably connected whereby to form a cylindrical casing adapted for disposal in a horizontal position, end plates closing the ends of the casing thus formed, and one of which end plates is apertured for the passage of a discharge pipe therethrough, each of said sections of 30 said casing being provided with an upper clean out hole which is adapted for the reception of an inlet pipe when desired.

GEORGE RALPH PAYNE.
STEWART MOORE.
